US00D993336S

(12) **United States Design Patent** (10) **Patent No.:** **US D993,336 S**
(45) **Date of Patent:** **** Jul. 25, 2023**

(54) **PAIR OF JUMP ROPE HANDLES**

(71) Applicant: **STORM AGE TECHNOLOGY (SHENZHEN) CO., LTD.**, Shenzhen (CN)

(72) Inventor: **Xueran Zhang**, Shenzhen (CN)

(73) Assignee: **STORM AGE TECHNOLOGY (SHENZHEN) CO., LTD.**, Shenzhen (CN)

(**) Term: **15 Years**

(21) Appl. No.: **29/797,524**

(22) Filed: **Jul. 1, 2021**

(51) LOC (14) Cl. **21-01**

(52) U.S. Cl.

USPC **D21/672**

(57) **CLAIM**

The ornamental design for a pair of jump rope handles, as shown and described.

DESCRIPTION

FIG. 1 is a perspective view of a pair of jump rope handles showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the pair of jump rope handles that form no part of the claimed design.

1 Claim, 8 Drawing Sheets
